APPARATUS FOR SECURING FOLDED PORTIONS OF PACKAGES

Alfred German Rose, Gainsborough, England, assignor to Rose Brothers (Gainsborough) Limited, Gainsborough, England, a British company

Application December 2, 1931, Serial No. 578,554
In Great Britain December 3, 1930

8 Claims. (Cl. 93—2)

This invention relates to apparatus, for use in conjunction with a wrapping or package-forming machine, for receiving and stacking the wrapped articles or packages.

5 The invention is applicable to packages of rectangular or similar block shaped form which comprise articles or groups of articles (e. g. bundles of cigarettes) enclosed in containers of paper, cardboard or like sheet material having folded portions secured by gum or other adhesive.

10 The main object of this invention is to provide an improved construction of stacking magazine for receiving the packages, pressing the overlapping folds into close contact with each other, without distorting the shape of the package or otherwise damaging it, and maintaining said contact until attachment of the folded portion has been accomplished by the drying of the adhesive.

15 A further object of the invention is to furnish a magazine in which provision is made for opening and closing one or more of the magazine walls, thereby to give access to the interior of the magazine and permit of inspection of the packages therein or their removal therefrom, without interrupting the continued upward feed of the packages through the magazine.

20 A still further object of the invention is to make provision for relative adjustment between opposed walls of the magazine in order to adapt it to handle packages of different size.

25 The invention provides for use in conjunction with a wrapping or package-forming machine, a tubular stacking magazine which is adapted to receive the packages and is characterized in that its interior walls, which will contact with overlapping folded portions of each package, are wholly or in part constituted by portions of the peripheral surfaces of rotatable rollers.

30 In one form the stacking magazine has a rectangular throughway whereof at least one wall, over the whole or a substantial portion of its length, is constituted by portions of the peripheral surfaces of a series of rollers which are mounted for rotation about parallel axes located in one and the same plane, and are so dimensioned and arranged in relation to the packages to be handled that during movement of the latter through the magazine there will be at least one of the aforesaid series of rollers in contact with the adjacent edge of each package.

35 According to a feature of the invention the rollers, or some of them, are arranged to exert a resilient pressure on the edges of the packages, and preferably the rollers constituting at least one

wall of the magazine are adjustable as a whole towards and away from the opposite magazine wall.

40 A further feature of the invention resides in having two opposed walls of the magazine so hingedly mounted at their edges that they may be opened and closed like doors, combined with manually operable catches for locking the walls aforesaid in their closed positions.

45 An example embodying the foregoing and other features of the invention will now be described with reference to the accompanying drawings in which:—

50 Figure 1 is a perspective view showing the type of package on which the apparatus is adapted to operate.

55 Figures 2, 3 and 4 are respectively side, front, and plane views of the stacking magazine, and

60 Figure 5 is a section showing the method of mounting certain of the magazine rollers.

65 Like reference numbers indicate like parts throughout the drawings.

70 Referring to Figure 1, the packages upon which this particular apparatus is arranged to operate are block-shaped as shown, each comprising an article such as a bundle of cigarettes or a cigarette-containing carton, enclosed in a wrapper which has been folded about one end 10 and over the top and bottom sides of the article to form an open-ended pouch, the overlapping edge portions 11 being closed in and finally the projecting portions 12 at the opposite end being closed as shown.

75 Conveniently the above folding operations are performed while the articles are being advanced one at a time by a horizontal conveyor in a wrapping machine of the kind described in U. S. specification No. 1,618,025. This specification describes a machine in which the articles are

80 traversed by pushers on an endless chain and during their forward motion are completely wrapped in paper, the wrapping operations being chiefly effected by stationary ploughs but a tuck at the end of each package being made by fingers which remove the package from the conveyor.

85 During the sequence of the wrapping operations gum or other adhesive is applied to the overlapping portions 11, 12 of the wrapper. The packages are fed one at a time to the lower end of the stacking magazine, each package on arrival at the magazine being supported on a platform 13 which is given a motion of vertical reciprocation

90 in step with the mechanism (not shown) which feeds the articles horizontally to the magazine. During the upward movement of the platform 13

the package (indicated at 14 in chain lines in Figure 2) supported on it and those above it are pushed upwardly in the magazine, and during the downward movement of the platform into a position ready to receive the next package from the horizontal conveyor, the packages in the magazine are constrained against downward movement by means which will hereinafter be described. If desired the final end flaps 12 may be closed while the package is supported on the platform 13 in a manner similar to that described with reference to Figures 18 and 19 of U. S. specification No. 1,618,025 aforesaid, that is to say the top one folded down by the edge of the magazine as the package is lifted and the bottom one folded up by a reciprocating blade. That is one method of closing the end of the package but it does not form any part of the present invention and it is to be understood that any other convenient method of folding the wrapper may be employed.

The stacking magazine is of tubular form, the cross section of its throughway being of rectangular shape conforming to the plan configuration of the packages to be handled.

The stacking magazine comprises a fixed end plate 15, two opposite side plates 16, 17 pivotally mounted, and a non-pivotally mounted but otherwise adjustable end plate 18. The fixed end plate 15 is provided with a foot piece 19 adapted to be bolted to a bracket or the like (not shown) on the wrapping machine. The two side plates 16, 17 are secured, in the manner hereinafter described, to brackets 20, 21 respectively which are pivotally articulated to the fixed end plate 15. For this purpose the end plate 15 is provided with lugs 22 carrying pins 23 on which the brackets 20, 21 are hinged. The opposite end plate 18 is secured to a bracket 24 which in turn is fastened to a pillar 25 bolted to the machine frame.

The inner face of the fixed end plate 15 is channelled to accommodate a vertical series of rollers 26 which are piled one on top of the other, the lowermost one resting upon a shelf 27 located at the foot piece 19. Each of the rollers 26 is provided at its opposite ends with pins 28 which are located in grooves 29 in the end plate 15. The whole length of the end plate 15, i. e. throughout the height of the magazine, is occupied by the rollers 26, so that the magazine wall with which the end 10 of the package will contact during its ascent in the magazine is constituted by a succession of cylindrical surfaces. As shown in Figure 2, the diameter of each of the rollers 26 is rather less than the depth of the package 14, so that during the upward movement of the latter, there will always be at least one roller in contact with the package end.

The opposite end plate 18 also carries a series of rollers, viz. those identified as 30, arranged in a vertical tier with their axes horizontal. These rollers do not rest one upon the other like the rollers 26, but are mounted in the manner shown in Figure 5. As will be seen each of the rollers 30 is rotatable on pins 31 which extend into bearings 32 at opposite ends of the roller and are secured to plungers 33 which in turn are received in channels 34 in the end plate 18. Each plunger is urged outwardly by a spring 35, and the extent of the outward movement of the plungers (i. e. away from the plate 18) is limited by flange plates 36 secured to opposite edges of the end plate and forming abutments for shoulders on the plungers. With this arrangement it will be seen that the end plate 18

may be so located that each of the rollers exerts a resilient pressure on the end 12 of the package. As before the rollers 30 are so dimensioned and arranged that during the ascent of the package at least one of the rollers will always be in contact with the end of the package.

The two pivotally mounted side plates 16, 17 also carry sets of rollers 37, 38 arranged in the same way as the rollers 30 of the end plate 18 and resiliently mounted on the plates in the manner illustrated in Figure 5. The lowermost rollers of the two sets 37, 38 are located, as shown in Figures 2 and 3, some distance above the lower ends of the side plates 16, 17, and the intervening space is occupied by brushes 39 which are provided for the purpose of gripping the opposite side edges of the packages in the lower portion of the magazine.

In order that the magazine may be adjusted to accommodate packages of somewhat different size the following arrangement is adopted. Two of the walls of the magazine, namely those constituted by the rollers 30, 37 are made adjustable towards and away from the opposite walls respectively of the magazine. For this purpose each of the plates 18, 16 is supported from its companion bracket 24 or 20 by two pairs of screw-threaded bolts 40 located near the upper and lower ends respectively of the plate 18 or 16. The bolts 40, which at their inner ends are secured to the plate 18 or 16, pass freely through apertures 41 in the bracket 24 or 20 and at their outer ends are engaged by nuts 42 formed with knurled manipulating heads 43. The plates 18, 16 are, as shown in Figure 4, spaced apart from the brackets 24, 20, and in the gap between them the stems of the bolts 40 are surrounded by springs 44 in compression. It will be understood that by manipulation of the nuts 42 the plates 18, 16 may be adjusted towards and away from the companion brackets 24, 20, and in this way the cross section of the magazine throughway may be varied.

It has been pointed out that the brackets 20, 21 which carry the side plates 16, 17 are pivotally mounted on the fixed end plate 15. This arrangement is adopted in order that the magazine may be opened and closed to permit inspection of the packages without necessitating their removal from the magazine nor causing any interruption in their upward feed. Either one or each of the side plates 16, 17 with, of course, the rollers carried by it, may be opened by swinging the appropriate bracket 20 or 21 outwardly about the hinge pin 23. In order that the two side plates 16, 17 may be locked in their closed position, two manually operable catch levers 45 are provided. These levers are pivotally mounted on a pin 46 secured to the fixed end plate 15 and at their outer ends are provided with handle portions 47. Near their outer ends the two catch levers are formed with U-shaped clips 48 adapted (when the catch levers are in a horizontal position) to be engaged over pins 49 fixed to the brackets 20, 21.

It will be seen that when either of the catch levers 45 is engaged over its corresponding pin 49, the corresponding side plate 16 or 17 is locked against opening movement. On the other hand when the catch lever is swung upwardly into a vertical position, the corresponding side plate is free to be opened like a door thereby giving access to the interior of the magazine.

As shown in Figure 4 each of the three plates 16, 17 and 18 is formed at the back with a

recess 50 which is adapted to accommodate a heating device, conveniently one of electrical type. These heating devices are provided for the purpose of ensuring that during the ascent 5 of each package in the magazine, the adhesive employed for attaching the overlapping side and end portions 11, 12 of the wrapper, will be completely dried.

It will be understood that as the packages are 10 fed upwardly in the magazine by reciprocation of the platform 13, the rollers 30 will exert a resilient pressure on the end folds 12 of the package while the rollers 37, 38 will similarly exert a resilient pressure on the longitudinal folds 11 of 15 the package. In this way the overlapping folds of the wrapper are maintained in correct register and in close contact with each other while the packages are moving through the magazine and the adhesive is setting. During the downward 20 movement of the platform 13 it is necessary to ensure that the packages in the magazine will be prevented from gravitating down it, and it is for the purpose of assisting such action that the brushes 39 are provided. These brushes are arranged 25 to press against the packages with their bristles sloping upwardly so as to offer greater resistance to downward movement of the packages than to upward movement.

I claim:

30 1. For use in conjunction with a wrapping or package forming machine a substantially vertical tubular stacking magazine comprising at least two sets of anti-friction rollers mounted within the magazine to constitute two opposed internal surfaces thereof, means for inserting packages at the bottom of the magazine and means for preventing substantial downward movement of the packages within the magazine.

2. For use in conjunction with a wrapping or 40 package forming machine, a substantially vertical tubular stacking magazine wherein the lower part of the internal surface of at least one of the walls of the magazine comprises a brush with the bristles directed inwardly and wherein the internal surfaces of at least two opposing walls above the brush comprises a plurality of anti-friction rollers rotatably mounted to turn about axes transverse to the throughway of the magazine.

50 3. For use in conjunction with a wrapping or package forming machine, a substantially vertical tubular stacking magazine of rectangular cross-section comprising two sets of brushes located near the bottom of the magazine with their bristles forming parts of opposed interior walls of the magazine, a plurality of sets of anti-friction rollers and means for supporting the rollers in each set close to one another with their axes extending parallel to one another in the same vertical plane and transverse of the throughway of the magazine and with the peripheral surfaces of the rollers constituting interior surfaces of the magazine above the brushes.

4. For use in conjunction with a wrapping or 65 package forming machine, a substantially vertical tubular stacking magazine of rectangular cross-section comprising two sets of brushes located

near the bottom of the magazine with their bristles forming parts of opposed interior walls of the magazine, a plurality of sets of anti-friction rollers and means for supporting the rollers in each set close to one another with their axes extending parallel to one another in the same vertical plane and transverse of the throughway of the magazine and with the peripheral surfaces of the rollers constituting interior surfaces of the magazine above the brushes and a reciprocable pusher movable into the bottom of the magazine from outside.

5. For use in conjunction with a wrapping or package forming machine, a substantially vertical tubular stacking magazine of rectangular cross section comprising two sets of brushes located near the bottom of the magazine with their bristles forming parts of opposed interior walls of the magazine, a plurality of sets of anti-friction rollers of less diameter than the vertical height of the package to be inserted into the magazine, and means for supporting the rollers in each set close to one another with their axes spaced apart by less than the vertical height of the package to be inserted into the magazine and extending parallel to one another in the same vertical plane and transverse of the throughway of the magazine and with the peripheral surfaces of the rollers constituting interior surfaces of the magazine above the brushes. 100

6. For use in conjunction with a wrapping or package forming machine, a substantially vertical tubular stacking magazine wherein the lower part of the internal surface of at least one of the walls of the magazine comprises a brush with the bristles directed inwardly and sloping upwardly and wherein the internal surfaces of at least two opposing walls above the brush comprise a plurality of anti-friction rollers rotatably mounted to turn about axes transverse to the throughway of the magazine. 110

7. For use in conjunction with a wrapping or package forming machine a substantially vertical tubular stacking magazine comprising at least two sets of anti-friction rollers mounted within the magazine to constitute two opposed internal surfaces thereof, means for inserting packages at the bottom of the magazine and means for preventing substantial downward movement of the packages within the magazine and means for heating 125 the magazine.

8. For use in conjunction with a wrapping or package forming machine, a substantially vertical tubular stacking magazine of rectangular cross-section comprising two sets of brushes located near the bottom of the magazine with their bristles forming parts of opposed interior walls of the magazine, a plurality of sets of anti-friction rollers constituting at least two opposed walls of the magazine above the brushes and mounted on 130 plates, with a recess in at least one plate, with their axes extending parallel to one another in the same vertical plane and transverse of the throughway of the magazine and heating means located in the recessed plate. 135

ALFRED GERMAN ROSE.
